INVENTOR

Harry E. McKee
BY
Charles L. Wright
ATTORNEY

UNITED STATES PATENT OFFICE.

HARRY E. MCKEE, OF BROOKLYN, NEW YORK.

STEM HANDLE.

Application filed March 17, 1924. Serial No. 999,675.

To all whom it may concern:

Be it known that I, HARRY E. MCKEE, a citizen of the United States, and a resident of Brooklyn, in the county of Queens and State of New York, have invented new and useful Improvements in Stem Handles, of which the following is a specification.

This invention relates to improvements in stem handles, valves, faucets and like apparatus.

The principal object of the invention is to provide means for detachably engaging the handle to its stem in a firm and secure manner.

Another purpose is to produce means for effecting positive engagement that permits axial adjustment of the handle relative to the stem and which avoids the use of set screws and like objectional elements.

A further aim is in the provision of an adjustable coupling device that can be cheaply constructed, easily applied and which presents a neat and attractive appearance.

These and analogous aims and objects which will later appear, are accomplished by the novel construction, combination and arrangement of parts hereafter described and shown in the accompanying drawing, forming a material part of this disclosure, and in which:

Figure 1 is a side elevational view of a conventional type of stem handle, parts being shown in section.

Figure 2, is a bottom plan view of the stem handle in detail.

Figure 3 is a plan view of the gripping member.

Figure 4 is a side elevation of the top part of the stem.

Figure 5 is a side elevational view of a modified form of stem handle.

Figure 6, is a bottom plan view of the same.

Figure 7 is a plan view of a modified form of a gripping member.

Figure 8 is a side elevational view of a modified form of the top part of the stem.

Figure 9 is a top plan view of the handle as shown in either figures 1 and 5.

Valves as used in plumbing in connection with wash bowls, bath tubs, sinks, wash tubs, etc., etc., usually have fixed on their handles, ordinarily in the form of a small wheel, a word, as Hot, Cold, Shower, and so forth, denoting the nature of the liquid controlled

by the valve and it is obviously desirable that the word or symbol used be so disposed as to be clearly and unmistakably read, particularly when the valve is closed, that is to say the word should be level and right side up.

This condition precludes having a label bearing handle fixed to the valve stem at random, for the reason that there is no assurance as to the position the word or mark may assume when the valve is closed and further, the position of the stem may vary from time to time, due to reseating or repacking of the valve, rendering relative adjustment highly important.

Such adjustment is usually made by fitting the hand wheel or handle to the stem, commonly reduced at its outer end and frequently ribbed or corrugated, and held in adjustment by a set-screw.

Such setscrews interfere with the fingers of a person operating the handle, often causing minor injuries and are always unsightly, besides frequently failing to hold, perhaps at a critical moment.

The present invention avoids all such untoward occurrences and disadvantages, forming a neat and secure, adjustable but positive connection as will now be set forth:

Referring more in detail to the drawing, the numeral 15 designates in general a valve stem having the usual operative elements not shown at its lower end and being revolvable in the body of the valve as will be clearly understood.

The upper end of the stem, as shown in Figures 1 and 4, is reduced in diameter and provided with a screw-thread 16, and has a short intermediate squared portion 17.

The handle element, generally designated by the numeral 18, is composed of a body 19, having a plurality of extensions, equally spaced and terminating in spherical members 20 adapted to be firmly grasped by the hand of an operator in actuating the valve.

A dome shaped element 21 is raised from the body 19, at its center and set rigidly in the same is a panel 22 bearing an inscription 22' denoting the purpose of the valve or the material it controls.

Extending from the opposite, or lower side of the body 19 is a hub 23 having on its exterior a screw-thread 24 and containing an axial screw threaded opening 25, the same being suited to receive the threaded portion 16 of the valve stem.

A collar or ring 26, of slightly less diameter than the threaded portion of the hub 23, is formed with a substantially square opening 27 to engage on the stem element 17, being prevented thereby from rotation, and on the outer edge of the collar are a plurality of teeth 28 of any preferred shape and engageable with corresponding teeth 29 on the end of the hub 23.

This collar abuts a shoulder 30 formed in a clamp nut 31 suited to engage the threads 24 of the hand wheel hub 23, this nut having an enlarged rim 32 adapted to be engaged by a wrench or other gripping device by which the nut may be rotated, forcing the toothed collar 26 into intimate and positive engagement with the end of the hub and, as it has been seen that the collar cannot turn, acts as a lock maintaining the handle 18 from rotating relative to the stem.

It will be apparent however that the handle may be turned by the relaxing of the nut 31 to allow separation of the teeth and then re-adjusted as desired to be again rigidly fastened.

In the modified form shown in Figures 5, 6 and 8, the squared element 17 of the stem is omitted and a slot 36 formed through the lower portion of the threaded element 16.

The end of the handle hub 23 is formed with semi-circular radial recesses 37 adapted to receive a pin 38 freely movable in the slot 36 and pressed into engagement by a thin ring or collar 39 abutting the interior shoulder of the clamp nut 31 as before described.

From the foregoing it will be seen that both devices are essentially similar and each is capable of accomplishing the stated purposes in a practical and efficient manner.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:—

1. A valve stem provided with a separable handle having a hub and teeth at the end of the hub, the stem having teeth on its end to adjustably engage with the teeth of the

hub, and means for rigidly securing the handle on said stem.

2. A valve stem having a screw threaded outer portion, a handle having a hub engageable on said threaded portion, the end of said hub being corrugated, a clamp nut engaging the exterior of said handle hub, and means actuated by said nut to co-operate with the end of said hub so as to be held non-rotatable relative thereto, said means being nonrotatively engaged on said stem.

3. A valve stem having a screw threaded outer portion, a handle having a hub engageable on said threaded portion, spaced radial teeth on the end of said hub, a clamp nut engaged on the exterior of said hub, a sleeve in said nut held nonrotatably on said stem, and means on said sleeve engageable with the teeth on said hub when said nut is tightened on the hub.

4. A valve stem having a screw threaded outer portion, a handle having a hub engageable on said threaded portion, spaced radial teeth on the end of said hub, a clamp nut engaged on the exterior of said hub to envelop the screw threads thereon, said nut having a wrench engaging portion and containing an axial shouldered recess through which said stem extends, a collar slidable on the end of said stem, means for preventing relative rotary movement between said collar and stem, said collar being arranged internally of said nut to abut the shoulder therein, and means associated with said collar adapted to engage said teeth when the nut is tightened on said hub.

5. A valve stem having a screw threaded outer portion, a handle having a hub engageable on said threaded portion, spaced radial teeth on the end of said hub, a clamp nut engaged on the exterior of said hub, to envelop the screw threads thereon, said nut having a wrench engaging portion and containing an axial shouldered recess through which said stem extends, a collar slidable on the end of said stem, said stem having a squared portion at the base of its screw-threads to which said collar is fitted, and teeth on one end of said collar engageable with the teeth of said hub, the opposite end of said collar abutting the shoulder in said nut.

In testimony whereof I have signed my name to this specification.

HARRY E. MCKEE.
